UNITED STATES PATENT OFFICE.

HENRY S. HALE, OF PHILADELPHIA, PENNSYLVANIA.

COMBINED SHOE AND LEGGING.

1,258,560.

Specification of Letters Patent.

Patented Mar. 5, 1918.

Application filed March 31, 1916. Serial No. 87,916.

To all whom it may concern:

Be it known that I, HENRY S. HALE, a citizen of the United States, and resident of Philadelphia, county of Philadelphia, and 5 State of Pennsylvania, have invented an Improvement in Combined Shoes and Leggings, of which the following is a specification.

The object of my invention is to provide a suitable combined shoe and legging which 10 may be easily applied and removed, and when in use snugly fit the foot and leg. My invention is more especially intended for embodiment in riding boots and which may be worn in the house without the legging or 15 puttee portions and with capacity for quickly attaching the latter when ready for the outside use, the combination being such that the two parts are positively coupled when applied as effectually for all practical purposes as if they were permanently united.

My object is further to form the riding boot of separable shoe and legging portions whereby they may be detachably connected so as to permit the replacing of a worn shoe 25 portion by a new shoe while retaining the continued use of the legging or puttee portion.

A further object of my invention is to provide shoe portions which are detachable from 30 the legging portions whereby in the commercial handling of the goods a number of sizes of shoe portions may be used with a single size of legging portion, and vice versa, so that a combined shoe and legging may be 35 assembled which will be a satisfactory fit. In this manner a store is enabled to carry less stock and yet be capable of filling the requirements of any person.

For the purpose of illustrating my invention, I have hereinafter set out various embodiments of my invention by way of example, they being best suited to give a clear and comprehensive understanding of the more essential features of the invention.

Referring to the drawings:—Figure 1 is a side elevation of a riding boot embodying my invention, a portion being broken away to show the structural features; Fig. 2 is a similar view (with the upper portion of the legging and toe portion broken away) showing a modified form of my invention; Fig. 3 is a perspective view of the coupling iron of the structure shown in Fig. 2; Fig. 4 is a sectional elevation showing a special locking means for the heel; and Fig. 5 is a detail of the lock employed in Fig. 4.

2 is the shoe portion and may be made in any suitable manner, and preferably provided with a heel 3. This shoe 2 is such that when separated from the legging 4, the foot 60 may be easily thrust into the shoe. I have not shown any definite way of making this shoe as it may be formed in any desired way but following the most approved art in shoe making of the type resembling slippers, the 65 height at the heel portion 2^a being preferably only such as will protect the rear of the foot and remove undue strain upon the heel extension or back stay portion of the legging, and thereby prevent objectionable binding 70 upon the instep portion. While I prefer a reasonable height to the back or heel portion 2^a, I in no wise restrict myself thereto, as the essential feature of the shoe is only that it may be easily applied and used without the 75 legging when in the house. At the instep portion of the shoe, I prefer that it shall extend well up to form a protecting tongue portion 2^b having side edges sloping backward and downward to the rear and over 80 which the lower forward edges of the legging may extend as clearly shown.

The legging portion 4 may be of leather and formed in any suitable manner; as shown, it is split vertically and wraps about 85 the leg with the vertical edges overlapping as at 7 and held in such position by separate buckles 5, 5, and 6, or by one long strap, it being immaterial to my invention just what closure means may be employed, since any 90 of those means heretofore in use may be availed of, if so desired.

In shape, the lower portion of the legging 4 may overlap the tongue portion 2^b of the shoe and fit well down to the instep and extend down at the sides to approximately the forward part of the heel 3, while the rear portion fits around the back foxings at the back of the upper of the shoe. That portion of the legging which fits upon the instep 100 portion may be tightened to the requisite degree by the strap and buckle 6 so as to make the joint at this place reasonably dust and rain proof, the overlap acting to shed the rain in an effective manner. To properly 105 hold the legging down to the shoe and the shoe tightly upon the foot, provision must be made for coupling the lower part of the legging and the heel portion of the shoe and this may be accomplished in a number of 110 ways, several of which are illustrated.

Referring more particularly to Fig. 1, it

will be seen that while the shoe 2 has a heel 3, it is inclosed by an outer heel 8 attached to the lower edge of the legging, said heel 8 having a metal bottom plate 9 which extends upward in front of the heel 3 of the shoe, and is provided with an inturned hooked end 10 fitting into a transverse notch 11 in heel 3. In fact, the parts 8 and 9 form a hollow heel upon the lower part of the legging, and into the recess in which the heel 3 of the shoe 2 is received. It will be understood that when the straps 5 and 6 are loosened, the legging would be attached by first inserting the inturned or hooked end 10 into the notch of the heel 3 of the shoe, and then lifting the rear of the legging and wrapping it about the leg and tongue of the shoe where it is securely fastened by the buckle straps 5 and 6. In this condition, the heel of the legging will shield and contain the heel 3 of the shoe, and the two parts will be locked together so that in ordinary walking there will be no separation or objectionable movement of the legging on the shoe.

In the construction shown in Figs. 2 and 3, we have the same general structure of the shoe and of the legging portion as found in Fig. 1, but in this case there is no heel on the legging which incloses the heel 3 of the shoe. In this case I have shown a metal frame 12 which is riveted in position at 13 to the lower edge of the legging 4, and the forward edges of this frame 12 are united in a cross bar 10^a which engages the notch 11 in the heel portion 3 of the shoe, and in this manner holds the legging from moving backward or upward and permits the straps 5 and 6 to be tightened to the requisite degree so that the legging and shoe practically operate as if they were a unit.

In Fig. 4, I have shown another modification of the hollow heel for the legging. In this case the heel 8^c is of stamped sheet metal and the shoe heel 3 is provided on the bottom with a recess 3^b and a plate 3^a which is provided with a bolt slot 3^c (see Fig. 5), and the outer heel 8^c is provided with a turn bolt 14 which may be rotated to lock the two heel parts 3 and 8^c together.

All of these various constructions illustrate modifications of my general invention in which the legging and the shoe portions are detachable, but are connected in such manner that a tight fit is made around the instep, and in walking the legging or puttee

will be properly associated with the shoe so that comfort and ease will be had, and therefore these constructions are shown by way of example and not as restriction. 60

It will now be apparent that I have devised a novel and useful construction which embodies the features and advantage enumerated as desirable, and while I have in the present instance shown and described the 65 preferred embodiment thereof which has been found in practice to give satisfactory and reliable results, it is to be understood that I do not restrict myself to the details, as the same are susceptible of modification in 70 various particulars without departing from the spirit or scope of the invention.

Having now described my invention, what I claim as new and desire to secure by Letters Patent, is:— 75

1. In a combined shoe and legging, the combination of a shoe having a heel, with a legging portion wholly separable from the shoe and fitting down over the rear part thereof so as in effect to form a detachable 80 continuation thereof, and means secured to the lower part of the legging and mechanically engaging the heel of the shoe for holding the legging from rising upward upon the shoe. 85

2. In a combined shoe and legging, the combination of a shoe having a heel, with a legging portion wholly separable from the shoe and fitting down over the rear part thereof so as in effect in form a detachable 90 continuation thereof, and means secured to the lower part of the legging and mechanically engaging the heel of the shoe for holding the legging from rising upward upon the shoe and also for providing an abutment 95 in front of the heel of the shoe for preventing the shoe moving forward relatively to the legging.

3. In a combined shoe and legging, the combination of a shoe having a heel, with a 100 legging portion fitting about the rear portion of the shoe, means for holding the legging portion tightly over the instep part of the shoe, and locking means for locking the lower portion of the legging portion to the 105 heel of the shoe.

In testimony of which invention, I hereunto set my hand.

HENRY S. HALE.
